UNITED STATES PATENT OFFICE

HARRY J. McMASTER, OF SEBRING, OHIO, ASSIGNOR TO THE SEBRING POTTERY COMPANY,
OF SEBRING, OHIO, A CORPORATION OF OHIO

COVERED DISH AND SIMILAR ARTICLE

Application filed May 12, 1930. Serial No. 451,743.

The invention relates to covered dishes and similar articles, and more particularly to a new and improved construction of verge or edge portion of such dishes.

It is present practice in the manufacture of covered dishes and the like to provide a shoulder at the upper open edge of the dish, upon which the cover is adapted to be seated, the verge extending upward around the edge of the shoulder and being so located that the cover fits upon said shoulder and entirely within the verge.

Such a construction of dish is unsightly when the cover is removed, and furthermore, in accordance with recent designs of dinner ware, many of such dishes are formed square or substantially square.

With such shapes difficulty has been experienced in producing covered dishes and the like as there is a great tendency for the dishes to warp and get out of shape in the drying or burning steps of the manufacture, since there is no strengthening or reinforcing structure to hold them in shape.

The object of the present improvement is to overcome the difficulties and objections to the present practice by providing a construction of verge which not only reinforces the dish and holds it against warping or getting out of shape in the drying or burning, but which also produces a much better appearance when the cover is removed from the dish.

The above and other objects may be attained by providing an inwardly disposed, substantially horizontal verge at the upper, open edge of the dish, whereby the cover may extend outward over the edge of the dish, producing a pleasing appearance when the cover is either upon the dish or removed therefrom, as well as reinforcing and bracing the upper edge portion of the dish and holding it in shape while the same is being dried or burned.

An embodiment of the invention is illustrated in the accompanying drawing, in which

Figure 1 is a top plan view of the improved dish, with the cover removed to illustrate the improved form of verge to which the invention pertains; and

Fig. 2, a vertical sectional view of the dish, with the cover thereon, taken as on the line 2—2, Fig. 1.

Similar numerals refer to similar parts throughout the drawing.

Although the invention relates to various covered articles of dinner ware and the like, a covered vegetable dish is shown in the drawings for purposes of illustration. This dish is generally indicated by the numeral 10, and comprises the bottom 11, and side walls 12, which may be of substantially square or rectangular form and slightly bowed outward, conforming to modern designs of dinner ware and the like.

Each of the side walls is provided at its upper edge with an inturned substantially horizontal verge 13 extending entirely around the upper edge and forming a flat, substantially horizontal, upper edge 15 upon which the flange 16 of the cover 17 may rest, the cover thus entirely covering the verge and extending outward over the edge of the dish. The cover 17 may also be provided with a depending vertical flange 16a inwardly spaced from the flange 16 and adapted to be located within the verge 13 to maintain the cover in position.

Thus when the cover is in place upon the dish it has a more pleasing appearance than the old form of dish in which the cover sits down inside of the verge.

It will also be seen, as shown in Fig. 1, that when the cover is removed the dish has a more finished appearance than the old form of dish.

The principal advantage of this form of verge, however, is that it reinforces and strengthens the plastic dish during the drying and burning operations. Particularly in the substantially square or rectangular dishes there is nothing in the old form of dish to hold the plastic material in shape until it is thoroughly dried and burned, while this inturned horizontal verge strengthens and reinforces the upper open edge of the dish and holds the side walls against warping or distortion until they are completely dried and burned.

I claim:

100

1. A covered dish and the like having a bottom and upwardly disposed side walls of substantially rectangular form, an inwardly disposed, substantially horizontal verge at the upper edge of and extending entirely around each side wall, the upper surface of the verge being substantially horizontal, and a cover having a flange around its outer periphery, the under surface of the flange being substantially horizontal and adapted to rest upon and entirely cover said upper surface of the verge.

2. A covered dish and the like having a bottom and upwardly disposed side walls of substantially rectangular form, an inwardly disposed, substantially horizontal verge at the upper edge of and extending entirely around each side wall, the upper surface of said verge being substantially horizontal, and a cover having a substantially horizontal flange around its entire outer periphery and a depending substantially vertical flange inwardly spaced from the horizontal flange, the horizontal flange being adapted to rest upon and entirely cover the upper surface of the verge, and the vertical flange being adapted to fit inside of the verge.

In testimony that I claim the above, I have hereunto subscribed my name.

30 HARRY J. McMASTER.
